UNITED STATES PATENT OFFICE.

BERNARD SUMMERFIELD, OF CHICAGO, ILLINOIS.

DETACHABLE HEEL.

1,396,299.

Specification of Letters Patent.

Patented Nov. 8, 1921.

Application filed September 23, 1920. Serial No. 412,192.

To all whom it may concern:

Be it known that I, BERNARD SUMMERFIELD, citizen of the United States, residing at Chicago, in the county of Cook and State 5 of Illinois, have invented certain new and useful Improvements in Detachable Heels; and I do hereby declare the following to be a full, clear, and exact description of the invention, such as will enable others skilled 10 in the art to which it appertains to make and use the same.

This invention relates to heels for boots and shoes and particularly to detachable metallic shell heels.

15 An object of this invention is to provide a heel which may be quickly and easily attached to a shoe, and which when attached will be of a design simulating the usual heel and without any of the attaching parts 20 exposed to view.

A further object of this invention is to provide an attachment for a heel to a shoe that will be strong and durable and that can be quickly, easily and cheaply manufactured.

With these and other objects in view the invention consists of the construction, the combination, the detail, and arrangement 25 of parts as hereinafter more fully described 30 and claimed.

In the drawings:

Figure 1 is a side elevation partly in section and partly broken away of a ladies' shoe with my heel attached and affixed in 35 place.

Fig. 2 is a fragmentary view of the same shoe as Fig. 1 with the heel partly attached.

Fig. 3 is a perspective of a fragmentary portion of the bottom of a shoe illustrating 40 the plate affixed to the shoe.

Fig. 4 is a detailed top perspective, illustrating each of the catch members in the form of an arch.

In detail the invention comprises a heel 45 A and a plate B attached to a shoe C. Heel A is provided with a countersunk screw hole 2 and catches 3 and 3^a and is otherwise hollow and has a top contour to conform to the contour of the shoe. Plate B is provided 50 with a pair of tongues 4 and 4^a to interlock with members 3 and 3^a as the heel is slid backward and is held seated by a screw 5 inserted through hole 2 and into a screw

threaded hole 6 in tongue 4^a which draws the locks 3 and 3^a and 4 and 4^a to their respective seats and thereby locks the heel in position. Plate B is suitably affixed to the sole or welt of the shoe as desired by nails 7 or by other suitable means.

It is obvious therefore that in assembling 60 the heel to the shoe all that is necessary is to press the heel against the bottom of the sole slightly forward of the normal position and slide it backward and insert screw 5 which is made with its head coplanar with 65 the front surface of the heel by reason of the countersink, and then the heel is completely assembled and all parts are hidden from view so that when suitably colored the heel is attractive and of the usual appear- 70 ance.

It is further obvious that all of the parts functioning in this attachment are completely concealed from view and are within 75 the shell of the heel.

It is further obvious that by reason of the evolved structure of the bridges in the heel shell that they serve both as braces for this shell and also as means for interlock and that a very strong and substantial fitting is 80 obtained and also a very strong and durable heel is obtained with minimum weight and without any complicated structure.

Claims:

1. A demountable heel attachment comprising a metallic plate, a pair of tongues struck out from said plate and disposed at an angle with respect thereto, said tongues being arranged in longitudinal spaced relation, a heel member hollow in cross section, 85 a pair of catches formed in the heel member and arranged in longitudinal spaced relation, said catches and tongues operative as interengaging latches upon the movement of said heel relative to the plate, means for affixing the plate to a shoe, one of said 90 tongues being adapted to come into juxtaposition to the front of the heel and means for anchoring said heel to the juxtapositioned tongue.

2. A demountable heel attachment comprising a perforated plate and means for affixing said plate to a shoe, a pair of longitudinally spaced tongues struck out from said plate and being disposed in an inclined 105 position, the lower ends of said tongues

being arranged at substantially right angles to the body portion of the tongues, a heel member hollow in cross section, a pair of catches in the body of the heel, said catches being adapted for engagement by the lower angular ends of the tongues on the plate to form interengaging latches upon the move-

ment of said heel relative to the plate, one of said tongues being adapted to come into juxtaposition to the front of the heel and means for anchoring said heel to the juxtaposed tongue.

In testimony whereof I affix my signature.
BERNARD SUMMERFIELD.
